(57) **CLAIM**

The ornamental design for a portion of a communications terminal display screen with a dynamic icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is the first image in a sequence for a display screen showing a dynamic user icon with the new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof; and,

FIG. 16 is the sixteenth image thereof.

The outermost dot dot dash line showing of the communications terminal display screen and all other broken lines showing of portions of the icon are included for the purpose of illustrating portions of the article and form no part of the claimed design. The subject matter in this patent includes a process or period in which an images changes into another image. This process or period forms no part of the claimed design.
